SIZE-REDUCING MILL

Charles F. Osgood, Claremont, N. H., assignor to
 Sullivan Machinery Company, a corporation
 of Massachusetts

Application November 29, 1935, Serial No. 52,051

15 Claims. (Cl. 83—9)

This invention relates to size-reducing mills, and more particularly to mills which are especially adapted for the reduction in size of masses or rock, ore, retort residues, coal or other materials, from sizes of a maximum diameter of several inches to sizes which will pass through a sieve of comparatively small mesh.

An object of my invention is to provide an improved size-reducing mill. Another object is to provide an improved size-reducing mill requiring a minimum amount of power in proportion to the amount of useful work performed. Still another object is to provide an improved mill in which a plurality of stages of reduction may be effected in a common zone. A further object of my invention is to provide an improved plural stage size-reducing mill in which a minimum of power will be required during periods of reduced or interrupted feed, and which will largely control its own rate of feed. A still further object of my invention is to provide an improved size-reducing mill in which the crushing action of relatively moving bodies may be availed of in a plurality of stages; and as a more specific object of my invention, in this direction, there is the provision of an improved mill in which one of the bodies may operate in a plurality of reduction stages. Still another object of the invention is to provide an improved size-reducing mill in which a preliminary stage of reduction, say from a size of comparatively large diameter, to a relatively small mean diameter may be accomplished, with a considerable part of the material reduced to the desired ultimate size, in a first stage, said mill providing as a further size-reducing means apparatus permitting relatively immediate discharge of the adequately reduced material and further size-reduction of the material inadequately reduced. Still another object of my invention is to provide in a plural stage size-reducing mill an improved construction in which the same element may perform the function of a casing within which one stage of reduction takes place and also the function of a breaking medium with respect to another casing in which a further stage of size-reduction is effected. Other objects and advantages of the invention will, however, hereinafter more fully appear.

In the accompanying drawing, in which one illustrative embodiment and a modification are shown for purposes of illustration,

Fig. 1 is a view in central vertical section through a size-reducing mill constructed in accordance with my invention.

Fig. 2 is a vertical section on a plane corre-

sponding to the section line 2—2 of Fig. 1, with certain parts shown in elevation.

Fig. 3 is a section similar to Fig. 2, showing a modified form of feeding apparatus.

Referring first to the embodiment of the invention illustrated in Figs. 1 and 2, it will be noted that a bed plate 1 provides an appropriate mounting 2 for a crank shaft 3, appropriately counterweighted as at 4 to provide smooth drive, and having thereon the combined drive pulley and fly wheel 5. The crank shaft 6 is connected by a suitable connecting rod 7 to a depending arm 8 secured to a shaft 9 journaled on a pair of upstanding brackets 10 which may be formed integral with the bed plate 1, or otherwise suitably mounted thereon. This shaft 9 supports in its central portion a tubular feed supply device 11 having a flared mouth at 12 to permit continuous communication with any suitable feed spout, not shown. The shaft 9 does not extend directly through the feed connection 11, but is connected to the opposite side thereof so that a continuous feed passage 13 may extend from the mouth 12 down to the lower end 14 of the member 11. The member 11 is provided near its lower end and at its opposite sides with pairs of ears 14' to which, through suitable transverse holding devices, herein bolts 15, there is connected a size-reducing chamber 16 in which the first stage of size-reduction within the mill is accomplished. Obviously, the chamber 16 may be secured to the member 11 in other ways, but the method illustrated, including the bolts 15 and a close central connection, as at 17, provides a very effective mounting.

The size-reducing chamber 16 is arcuate in form, and provides an arcuate size-reducing chamber 20 therein, which is of substantially uniform cross section on radial planes including the axis of the shaft 9; and the curve of the chamber 20 conforms to arcs struck from the axis of the shaft 9 as a center. The chamber 20 is somewhat elongated, indeed materially so, and preferably is longer at each side of its zone of communication 21 with the feed passage 13 than the width of that passage. The ends of the chamber may be suitably rounded, as at 22, both exteriorly and interiorly, and the walls of the chamber may be perforated, as at 23, to permit the discharge of adequately reduced material from the chamber 20, while preventing inadequately reduced material from escaping.

Within the chamber 20 is desirably provided, when hard material is to be reduced, an appropriate size-reducing medium, herein shown as in the form of a single ball 25, of appropriate ma-

terial and of a diameter not greatly smaller than the internal diameter, on a radial plane, of the chamber 20. Obviously, a plurality of size-reducing bodies might be used.

Surrounding the member 16 and supported by suitable bearings 30 from the shaft 9 is a second size-reducing chamber forming member 31. This is provided with a lower, generally arcuate, portion 32 connected to an upwardly extending portion 33, the portion 33 being formed to permit the necessary relative movement between the member 11 and the member 31. The chamber 32 is, in cross section on radial planes including the axis of the shaft 9, at all points, except as modified by its communication with the portion 33, quite closely similar to the outer transverse contour of the member 16. The chamber 32 is elongated, and it will be noted that, since the chamber forming member 31 and the chamber forming member 16 are each oscillatable about the axis of the shaft 9, and since they are of shapes conforming to arcs struck from the shaft 9, there will be relative movement between member 16 and member 31 which will not change appreciably anything except their relative longitudinal positions. In other words, the radial clearance between the exterior of the member 16 and the bottom and lateral walls of the chamber 32 will not be altered. The upper portion of the member 31 is formed to provide a relatively close fit at 36 for the outside of the member 11, but by reason of the fact that this fit occurs at the diametric plane through the axis of the shaft 9 no substantial friction will occur. The bottom wall of the member 31 is provided, in the illustrative embodiment, with a plurality of longitudinally extending, relatively narrow discharge passages 37, through which adequately reduced material will be discharged, and an appropriate launder 39 is arranged to receive material discharged through the passages 37.

Instead of employing an oscillating funnel or like construction, as shown in Fig. 1, for the delivering of material to be reduced in size to the feed passage 13, it is possible to enlarge the shaft 9 and to provide a feed passage extending axially through the latter, as at 40 in Fig. 3, such a passage communicating as at 41 with the feed passage 13; and to provide a feed connection 42 having a connection 43 with the bore of the hollow shaft 9.

The chamber 32 may be provided with appropriate wear resistance liners 45 of suitable material, as illustrated in Fig. 2, and the chamber may be formed with a removable side wall 46 to permit access to the interior and removal of the liners. The materials of which the chambers and the size-reducing medium may be constructed may obviously vary considerably, but those skilled in this art will be familiar with the preferable materials, as for example, chrome steel alloys and the like, which may be used when certain relatively hard substances are to be reduced; and if soft material, such as talc, is to be processed, obviously it would be possible to use rubber balls and rubber liners, if necessary, or other appropriately constructed chambers. However, the materials used, the relative sizes and weights of the parts, the nature and sizes of passages and openings all depend, more or less, on the substance to be processed; and it will be obvious that there may be wide variations, but all within the knowledge of those skilled in this art. It may be here noted that the outer chamber could be made stationary, or indeed may

be the sole directly actuated element, if conditions warrant.

The mode of operation of the invention may now be briefly described. Material to be reduced in size may be supplied to the opening 12 in Fig. 1, or to the passage 40 in the hollow shaft 9 in Fig. 3, and delivered through the feed passage 13, and enter the size-reducing chamber 20, wherein it will be reduced in size sufficient to pass through the discharge openings 23 formed in the walls of the casing 16. Of course, with materials of certain friability and other characteristics, the use of an internal size-reducing medium will be unnecessary, but for many materials the employment of an internal size-reducing medium, illustrated herein by the single ball 25, will be desirable.

Now it will be understood that power will be transmitted to the combined pulley and flywheel 5 and will cause the same to rotate, thereby to turn the crank shaft 3, and the connecting rod 7 and arm 8 will impart an arcuate oscillation to the casing 16 about the axis of the shaft 9. This will create a movement of the chamber contents including, when the same is present, size-reducing medium 25. The movements of the chamber member 16 will cause the chamber contents to undergo movements in which there will be periods of movement of the load with the chamber, periods of load movement relative to the chamber, and periods of impact or of compacting, at least, of the load within the chamber. Depending upon the angle of oscillation of the chamber and the length of the chamber and the length arcuately of the load within the chamber, there will be decided variations between relatively sharp impact and relatively dead, but powerful compacting of the charge with respect to the chamber. During the relative movement of the load within the chamber there will, of course, be a relatively continuous reduction in size of the fragments of material to be reduced within the chamber. There will be a reduction in size due to attrition, due to the radial pressure as a result of centrifugal force during the periods of arcuate movement of the chamber, and also due to the internal working of the particles making up the charge. There will be crushing force due to the compressive action of the medium upon the charge and the forces exerted by the medium and the walls, particularly the end walls, on the charge of material to be processed. Moreover, there will be a size-reducing action by the size-reducing medium against the lower wall of the chamber. In other words, there will be a size-reducing action of a highly effective type, and moreover, a definite controlled one, due to the selection exercised in determining the relative length of the chamber and its form and the rate of feed. The size-reducing medium and entering material will fill the chamber, as feed is supplied in adequate quantities, up to a certain maximum value, materially less than the full volume of the chamber, and new material will enter the chamber past the ends of this load within the chamber only as adequately reduced material passes from the chamber through the openings 23.

Now with respect to the material which is discharged through the openings 23 into the chamber 32, it will be understood that this material will be of varying size, the particles of maximum size being just small enough to escape through the openings 23, and the size of the material passing through these openings into the chamber 32 will vary downwardly to dust; with cer-

tain materials a considerable fraction of the material being reduced to the ultimate necessary fineness by the reducing process carried on within the chamber 20. The starting of oscillation of the chamber 16 and the supply of feed to the mill will cause a sudden starting of movement of the chamber member 31. As material commences to be discharged from the openings 23 into the chamber 32, a portion of it will sift through the slots 37 (which slots will be understood to be discharge orifices) and the material will be conducted by the launder to the point of delivery. A portion of the material will not, however, escape through these slots, and accordingly a sufficient mass of material will build up within the space within the chamber 32 so that the movements of the member 16 will, through the material, be transmitted to the chamber 32, thereby setting chamber-forming member 31 into motion; and thereafter there will be a relative movement between the member 16 and member 31, which will result from the imparting of movement to the member 31 by the member 16. The chamber-forming member 31 will be moved by the member 16 a certain distance in one direction. It will continue to move in that direction for a certain time after the member 16 begins to slow down, and it may continue its movement in that direction after the member 16 begins to reverse its direction of travel. What will occur will depend upon the relative length of the chamber 32 with respect to the length of the chamber-forming member 16. In any event, the member 16, as it reverses its direction, will, either with or without the occurrence of impact (depending upon the relative length and amplitude of movement), in due season effect a reversal of movement of the chamber 32, and a similar sequence of operations will take place, but with reversed movements, during the opposite passage of member 16. Now it will be evident that during the relative movement of the member 16 with respect to the chamber 32, there will be a very effective size-reducing action taking place, including a grinding action between the outer wall of the member 16 and the interior of the member 31, and a crushing action due to the forcible compacting of other particles of material between the exterior of the member 16 and the adjacent end walls of the member 31. There may be powerful impacts, depending upon the design and characteristics, secured by making the relative lengths and movements such that the chamber member 16 may attain its relative maximum velocity in the reverse direction before consolidation of the material between its leading end and the oppositely moving end of the chamber-forming member 31 occurs.

It will be evident, of course, that there will be attrition, due to centrifugal force, as the material within the chamber 32 is pressed by the centrifugal force against the walls of the chamber, and there will be constant internal working within the material in the chamber 32, due to the various forces to which it is subjected.

It is to be noted that if the feed to the feed connection 13 be interrupted, the quantity of material within the chamber 20 will soon be depleted, and until and after the feed is again started there will not be motion of such amplitude imparted by the chamber 16 to the size-reducing medium 25 as to cause impact; and in like manner the chamber-forming member 31 will no longer be positively maintained in motion by the member 16.

My invention may be employed in wet grinding operations as well as in the dry operations of size-reduction, and it is adapted to provide anything from a powerful impact type of reduction to reduction largely produced by attrition and internal working of the charge, depending upon the amplitude of motion and the amount of free travel provided between the positively oscillatable element and the cooperant parts. Automatic feed control to the first stage is secured, and by proper design of the second stage no amount of material which may be discharged from the first stage can ever choke the second stage.

It will be evident that this design is simple; that it has only one directly power-driven part; that this part cooperates to effect a plural-stage reduction; that the apparatus is rugged in construction, highly efficient, and adaptable to substantially any material whose size may require reducing.

While I have in this application specifically described one form, and a modification thereof, which my invention may assume in practice, it will be understood that this form and modification are shown for purposes of illustration, and that the invention may be further modified and embodied in various other forms without departing from its spirit or the scope of the appended claims.

What I claim as new and desire to secure by Letters Patent is:

1. In a mill, a frame, a pendulum pivotally supported on said frame for oscillatory movement and having an elongated arcuate chamber therein, means for positively oscillating said pendulum, a free spherical crusher element in said chamber constrained as to movement only by said chamber wall and having a diametric dimension of relatively the same order as the vertical dimension of said chamber, a pendulum member pivotally supported on said frame for oscillatory movement and having an arcuately elongated chamber therein receiving said pendulum and having walls cooperating with said pendulum in the further size-reduction of material, means for introducing material into said pendulum during movement of the latter, means for discharging material from said pendulum into said chamber in said pendulum member, and means for discharging material from said pendulum member.

2. In a size-reducing mill, a size-reducing member, means for positively moving the same alternately in opposite directions in a predetermined path, a casing providing a size-reducing chamber into which said size-reducing member extends and having supporting means providing for the free movement thereof in a path similar to the path of movement of said size-reducing member and having ends with which said size-reducing member cooperates in the size-reduction of material, said size-reducing member also having a size-reducing chamber therein, a size-reducing medium in said chamber last mentioned, said last mentioned size-reducing chamber having ends with which said size-reducing medium coacts in the size-reduction of material, means for feeding material into said mill comprising means for delivering all the material entering the mill initially to said last mentioned chamber, whereby material entering said first mentioned chamber must first pass through said last mentioned chamber, means for discharging material from said last mentioned chamber to said first mentioned chamber, and means for

discharging material from said first mentioned chamber.

3. In a size-reducing mill, a member providing an elongated size-reducing chamber having upper and lower walls, said size-reducing chamber containing a free size-reducing medium, means for supporting said member for oscillation about an axis located above said size-reducing chamber and for swinging said member alternately in opposite directions upon said axis, means for introducing material to be reduced in size into said chamber through the upper wall thereof at a point spaced from both ends of said chamber, means for discharging size-reduced material from said chamber, a casing member surrounding said first mentioned member and supported for pivotal movement about an axis adjacent its top and having material discharging means associated therewith, said 15 casing member providing a chamber receiving said first mentioned member and having ends coacting with the ends of said first mentioned member in effecting size-reduction, said means for discharging size-reduced material from said 20 first mentioned chamber communicating with said second mentioned chamber, and the axes of pivotal movement of said members lying in the same straight line.

4. In a size-reducing mill, a member providing an elongated size-reducing chamber containing a free size-reducing medium, means for supporting said member for oscillation about an axis located above said size-reducing chamber and for swinging said member alternately in opposite directions upon said axis, a casing member surrounding said first mentioned member and supported for pivotal movement about an axis adjacent its top and having material discharge means associated therewith, means for discharging size-reduced material from said first mentioned chamber into said casing member, said casing member providing a chamber receiving said first mentioned member and having ends coacting with the ends of said first mentioned member in effecting size-reduction of material delivered thereto from said first mentioned member.

5. In a size-reducing mill, a positively power oscillated crushing member providing all of the walls of a size-reducing chamber and having provision for the feed of material into the interior thereof, said member having its axis of oscillation located outside of said size-reducing chamber, a casing surrounding said member and freely pivotable about the axis of oscillation of said member and having a size-reducing coaction with said member, and means for feeding material into said casing from said member at opposite sides of the longitudinal center thereof and for discharging size-reduced material therefrom.

6. In a size-reducing mill, a positively power-oscillated crushing member providing all of the walls of a size-reducing chamber and having provision for the feed of material into the interior thereof, a casing surrounding said member and providing a crushing chamber therein into which said crushing member extends, said casing freely pivotable about the axis of oscillation of said crushing member and deriving its motion from the latter through material in process of reduction, means for feeding material into said crushing member, means for discharging 75 partially size-reduced material therefrom into

said casing, and means for discharging material from said casing.

7. In a size-reducing mill, a hollow member providing a size reducing chamber containing a free size-reducing medium, means for supporting said member and for imparting thereto alternate movements in opposite directions, means for introducing material into said chamber, means for discharging size-reduced material from said member, a casing member supported for movement and surrounding said member and providing a chamber receiving the latter and to which said means for discharging size-reduced material from said chamber discharges, said casing member also having material discharge means associated therewith and having its chamber of a size in the direction of movement of said hollow member slightly greater than the overall length of the path of movement of said hollow member, whereby upon, but only upon, a predetermined filling of the chamber in said casing does the latter receive motion from said hollow member.

8. In a size-reducing mill, a positively power oscillated crusher member pivotable about an axis adjacent its upper end and having a working, blow-striking outside, and furthermore having an internal preliminary size-reducing chamber, and means for delivering material to the latter, a casing pivotable about an axis from which it depends, said casing axis alined with the crusher chamber pivot, said casing having opposite ends with which the opposite faces of said crusher member may alternately coact in a crushing operation, means for delivering material from said preliminary size-reducing chamber into said casing, and means for discharging size-reduced material from said casing.

9. In a size-reducing mill, a positively power oscillated crushing member providing a size-reducing chamber therein, and having provision for the feed of material into the interior thereof, a casing surrounding said member and providing a secondary size-reducing chamber and cooperating with said power oscillated crushing member in a secondary size-reducing action, and freely pivotable relative to said power oscillated crushing member about the axis of oscillation of said member, and means for feeding material into said first mentioned size-reducing chamber, means for feeding material from said size-reducing chamber into said casing only from said crushing member and from the latter at opposite sides of the longitudinal center thereof, and means for discharging size-reduced material from said casing.

10. In a size-reducing mill, a positively power oscillated crushing member providing a size-reducing chamber therein, in eccentric relation to its axis of pivotal movement, and having provision for the feed of material into said chamber, a casing surrounding said chamber and freely pivotable relative thereto about the axis of oscillation of said member and having a size-reducing coaction with said member, and means for feeding material into said casing only from said member and for discharging size-reduced material from said casing.

11. In a size-reducing mill, a member providing an elongated arcuate size-reducing chamber, and alternately moved by power in opposite directions in an arcuate path to which the curvature of said chamber conforms, means including a direct feed passage leading from the exterior of said mill to said size-reducing chamber for 75

feeding material to be reduced in size to said chamber and means for delivering material reduced to a smaller size from said chamber, and a casing providing a chamber into which said member extends, and means supporting said casing for free movement in a path similar to the path of movement of said member, said casing freely movable relative to said member, and receiving size-reduced material from said first mentioned chamber, and providing for the discharge of further size-reduced material, and said casing having the chamber therein conforming in curvature at its bottom and ends to the curvature of the bottom and ends of said chamber providing member.

12. In a size-reducing mill, in combination, a size-reducing element moved alternately in opposite directions in a predetermined path and having an end wall extending transversely of such path, means for delivering material into said mill along a path in the planes of movement of said element, means cooperating with one of the opposite surfaces of said end wall to effect percussive size-reduction, means for delivering material so size-reduced to the opposite side of said end wall, and means cooperating with such opposite side of said end wall to effect a further percussive size-reduction of such material.

13. In a size-reducing mill, a chamber member alternately moved by power in opposite directions, and providing end walls at which a size-reducing action takes place; a casing providing a chamber into which said chamber member extends and supported for free movement relative to the latter in a path similar to the path of movement of said chamber member, and also providing end walls at which a size-reducing action takes place, means for discharging material from said chamber member into said casing, means for feeding all the material to be reduced in size in said mill first into the interior of said chamber member for reduction therein, and means for discharging size-reduced material from said casing.

14. In a size-reducing mill, in combination, a hollow, power reciprocated, size-reducing element elongated along its path of movement and having at each of its opposite ends, in terms of its reciprocatory movement, inner and outer end surfaces each extending generally transverse to the path of movement of said element, means cooperating with the interior of said element to provide at one of said inner end surfaces of the latter, a preliminary size-reducing operation, a member substantially enclosing said size-reducing element and between which and said element relative movement takes place and which has a surface extending generally transverse to the path of movement of said element and cooperating with one of said outer end surfaces on said size-reducing element to provide a successive stage of reduction of the material previously partially size-reduced at said first mentioned pair of cooperating surfaces, and means for delivering material, following said preliminary size-reducing thereof, into position for said successive stage of reduction.

15. In a size-reducing mill, in combination, a power moved size-reducing element swingable bodily alternately in opposite directions in a predetermined arcuate path, means cooperating with said element and between which and said element there is relative movement longitudinally of said path, and respectively inside of and substantially enclosing said element, to provide within the annular zone in which said arcuate path lies and of which it forms a part, by the coaction of said element and said cooperating means inside the same, a primary size-reduction of material within said element and, by the coaction of said element and said cooperating means substantially enclosing the same, a secondary size-reduction of the same material in a distinct stage outside said element, and means for delivering material following the primary size-reduction thereof inside said element to the exterior of the latter for said size-reduction outside said element.

CHARLES F. OSGOOD. 45
